UNITED STATES PATENT OFFICE.

JOSEPH N. SUPRUNOWSKI, OF MODE, ILLINOIS, ASSIGNOR OF ONE-HALF TO
DORAS E. ELLIOTT, OF SHELBYVILLE, ILLINOIS.

FOLDING COOP.

SPECIFICATION forming part of Letters Patent No. 626,109, dated May 30, 1899.

Application filed February 15, 1899. Serial No. 705,590. (No model.)

To all whom it may concern:

Be it known that I, JOSEPH N. SUPRUNOWSKI, a citizen of the United States, residing at Mode, in the county of Shelby and State of Illinois, have invented certain new and useful Improvements in Folding Coops; and I do hereby declare the following to be a full, clear, and exact description of the invention, such as will enable others skilled in the art to which it appertains to make and use the same.

This invention relates to that class of poultry coops or crates which are designed to be folded for the purpose of storing and shipment, so as to occupy the smallest amount of room possible.

The purpose of the invention is to prevent the loss or displacement of the parts of the coop and to insure the stability of the structure when unfolded and in condition for service; also, to simplify the general construction, whereby the folding and the setting up of the coop can be readily effected.

Other advantages are contemplated and will appear in the course of the following description, reference being had to the drawings here-to attached, in which—

Figure 1 is a perspective view of the coop unfolded. Fig. 2 is a longitudinal section showing the partition folded upon the bottom. Fig. 3 is a view similar to Fig. 2, showing the partition and sides folded and the body partly collapsed. Fig. 4 is a plan section. Fig. 5 is a transverse section. Fig. 6 shows the coop folded.

Corresponding and like parts are referred to in the following description and indicated in the several views of the drawings by the same reference characters.

The coop is collapsible and its parts are hinged or pivoted together, so as to prevent loss or displacement. The top 1, ends 2, and bottom 3 are hinged, so as to fold upon one another in parallel relation, as indicated in Figs. 3 and 6 of the drawings. The sides 4 are hinged at their lower edges to the side portions of the bottom 3 and are set in a short distance from the longitudinal edges of the bottom, so as to abut at their ends against the inner edges of cleats 5, applied to the extremities of the ends 2, whereby said sides are prevented from outward displacement.

The sides fit snugly between the ends 2 and abut at their extremities against the inner faces thereof, so as to prevent collapsing of the coop when unfolded or set up for use. The 55 inner sides 4 are adapted to fold inward and upon the bottom 3 and are provided upon their inner sides at an intermediate point with cleats 6. The partition 7, hinged at its lower edge transversely of the bottom 3, is adapted when unfolded to rest against the cleats 6 and brace the sides 4 and prevent inward movement thereof. This partition is formed in its top edge with a notch 8, forming a seat for the reception of the movable slat 9 of the top 1. 60 65

The slat 9 is pivotally connected at one end to an end cleat of the top 1 and is movable, so as to admit of ready access to the interior of the coop. Notches 10 are provided at opposite points in the edges of the slat 9 and 70 receive the portions of the partition bordering upon the notch 8, thereby preventing the folding of said partition when the slat is in position, as indicated most clearly in Fig. 1.

When it is required to collapse or reduce 75 the coop to a knockdown condition, the slat 9 is moved so as to disengage it from the partition 7, after which the latter is folded upon the bottom 3. The sides 4 being liberated are folded inward upon the bottom and partition, 80 thereby permitting the structure to fold as indicated in Fig. 3. The coop is held in a folded position by means of a chain 11, secured to the bottom 3 near one end and adapted to be engaged at its other end with the slat 9. When 85 it is required to set the coop up, the slat 9 is released and the body portion unfolded, after which the partition and the sides are unfolded in the manner set forth, thereby bracing the structure and maintaining it in condition for 90 service.

Having thus described the invention, what is claimed as new is—

1. A folding coop or like structure having parallel end pieces hinged at their lower edges 95 to the terminals of the bottom, a top parallel with the bottom and hinged at its extremities to the top edges of the end pieces, cleats applied to the extremities of the end pieces and projecting inward therefrom, inwardly-fold- 100 ing parallel side pieces hinged at their lower edges to the bottom and having their ends

abutting against the inner sides of the end pieces and against the inner edges of the said terminal cleats, and a partition for preventing inward displacement of the side pieces 5 when the coop is set up, substantially as described.

2. A folding coop or like structure having parallel end pieces hinged at their lower edges to the terminals of the bottom, a top parallel 10 with the bottom and hinged at its extremities to the top edges of the end pieces, cleats applied to the extremities of the end pieces and projecting inward therefrom, inwardly-folding parallel side pieces hinged at their lower 15 edges to the bottom and having their ends abutting against the inner sides of the end pieces and against the inner edges of the ter-

minal cleats, intermediate cleats applied to the inner faces of the folding side pieces, a partition hinged to the bottom and opening 20 against the said intermediate cleats and having a notch in its top edge, and a movable slat constituting an element of the top and having oppositely-disposed notches in its edges to embrace the sides of the partition 25 adjacent to the notch thereof, substantially as and for the purpose specified.

In testimony whereof I affix my signature in presence of two witnesses.

JOSEPH N. SUPRUNOWSKI. [L.S.]
